DESIGN FOR A DRESS

Eva Schetagne, New York, N. Y.

Application October 27, 1939, Serial No. 87,880

Term of patent 3½ years

To all whom it may concern:

Be it known that I, Eva Schetagne, a subject of the King of Great Britain, residing in the city, county, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

I claim:

The ornamental design for a dress, substantially as shown.

EVA SCHETAGNE.
